UNITED STATES PATENT OFFICE.

EDWARD A. REAP, OF OILTON, OKLAHOMA.

CAN.

Application filed September 27, 1926. Serial No. 138,002.

This invention relates to can or bottle construction, and aims to provide means whereby air may enter the can or bottle adjacent to the upper side thereof when the can or bottle is being held for pouring, to the end that the air will displace the liquid, allowing the liquid to flow in a steady stream.

Another object of the invention is to provide a removable closure for bottles, jars or the like, the closure being equipped with tubes of a novel construction to facilitate the pouring of the liquid from the container.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a can equipped with a discharge opening and spout constructed in accordance with the invention.

Figure 2 is a sectional view taken on line 2-2 of Figure 1.

Figure 3 is a longitudinal sectional view through a jar showing a removable closure equipped with a discharge tube.

Figure 4 is a sectional view taken at right angles to Figure 3.

Figure 5 is a sectional view taken on line 5-5 of Figure 3.

Referring to the drawing in detail, the reference character 5 indicates a can, which is provided with the usual discharge spout 6.

The discharge spout is divided by the member 7, which is constructed of sheet metal and as shown, is curved so that the side edges thereof may be readily secured within the curved surface of the discharge spout.

The length of sheet metal extends diagonally across the under surface of the top of the can as illustrated by Figure 1, the side

edges thereof being secured to the under surface of the top, the inner end thereof lying in spaced relation with the can to allow air to pass into the can. 50

Thus it will be seen that when the can is tilted to cause the liquid contained therein to discharge through the spout 6, air will 55 enter at a point adjacent to the upside of the can displacing the liquid held within the can.

In the form of the invention as illustrated by Figure 3, the reference character 8 designates a removable screw cap for a jar or the like, the same being provided with a central opening in which the tube 9 is positioned. This tube 9 is divided throughout a portion of its length by means of the partition 10, the partition 10 extending to a point adjacent to the bottom of the jar as clearly illustrated by the drawing. An opening 11 is formed in the inner end of the partitioning member and affords means of 70 communication between the tube 9 and interior of the jar.

Thus it will be seen that a jar equipped with a cover or cap of this character may when tilted, pour a steady stream of liquid 75 from the jar, owing to the fact that air may enter the jar at the bottom thereof.

I claim:

In a receptacle for containing liquids, a body portion having a threaded mouth, a 80 threaded cap for closing the mouth of the body portion, a tubular member secured within the cap, and extending into the body portion, one side of the tubular member being cut away from a point adjacent to 85 the threaded cap to the inner end thereof, a partitioning member extending throughout the length of the tubular member for dividing the upper portion of the tubular member into lateral compartments, and said partitioning member having a cut away portion 90 at its inner end for admitting fluid to the tubular member.

In testimony that I claim the foregoing as my own, I have hereto affixed my signature.

EDWARD A. REAP.
